UNITED STATES PATENT OFFICE

HARRY LEE CORWIN, OF LOS ANGELES, CALIFORNIA

DRAFTING INSTRUMENT AND ATTACHMENT

Application filed February 26, 1927. Serial No. 171,180.

This invention relates to instruments of the type known as self-adjusting spring bow compasses, commonly called "pile-drivers", and the principal object of the invention is to provide an instrument of this type which may be used for drawing or inscribing figures which are non-circular in shape, such as hexagons or squares or any polygonal figures, or ellipses or the like.

It is an object of this invention not only to provide a complete instrument for this purpose, but also to provide an attachment which may be applied to an ordinary "pile driver" or spring bow compass so as to enable it to be used for the purposes above mentioned.

The drafting instrument which I have devised for this purpose comprises in general a vertical central rod or member which is preferably pointed at its lower end, a scribing member rotatably mounted on said central member and having scribing means at its lower end, a template member secured or adapted to be secured to said central member, and means on said scribing member engaging said template member so as to cause the scribing means thereon to inscribe a figure of the same shape as said template member upon rotation of said scribing member. The template member is preferably detachably secured to the central member so as to permit template members of different shapes to be used for drawing correspondingly shaped figures.

Other features and objects of the invention will be apparent from the following description thereof.

The accompanying drawings illustrate embodiments of my invention and referring thereto,

Fig. 1 is a side elevation of an ordinary form of "pile driver" or self-adjusting spring bow compass, with certain additional parts attached thereto so as to enable it to perform the operations above described.

Fig. 2 is an end elevation thereof taken from the left in Fig. 1.

Fig. 3 is an end elevation taken from the right in Fig. 1.

Fig. 4 is a horizontal section on line 4-4 in Fig. 1.

Fig. 5 is an enlarged vertical section through the lower portion of the template member and the central member.

Fig. 6 is a view similar to a portion of Fig. 4 showing another form of template member.

Fig. 7 is a side elevation, partly broken away, of a pen attachment which may be used interchangeably with the pencil attachment shown in the preceding figures.

Fig. 8 is a partly sectional side elevation of the lower portion of a modified form of the invention.

Fig. 9 is a section on line 9-9 in Fig. 8.

The instrument shown in Figs. 1 to 5 inclusive comprises a central rod 1 having a sharp point 2 at its lower end for piercing a sheet of drawing paper or the like so as to hold such central member in fixed position and having a knurled handle or knob 3 at its upper end by means of which it may be manually held in position.

The scribing member may comprise a spring arm 5 carrying suitable scribing means such as a pencil attachment 6 at its lower end and mounted at its upper end upon supporting block 7 which is secured upon a tubular sleeve or bearing means 8. Said sleeve 8 surrounds the central member 1 so as to rotate freely around said central member.

The central rod 1, however, projects somewhat below the lower end of said sleeve, and the projecting portion of said rod is tapered as at 23. Limited relative vertical movement of the sleeve 8 with respect to central member 1 is also provided for, such movement being limited by small projections 9 on the central member, which limit the upward movement of sleeve 8 by engaging the bottom of recess 10 within said sleeve and limit the downward movement thereof by engagement with a bushing member 11 which may be screwed into the upper end of the said recess. Said bushing member may be provided with a knurled head 25 by means of which the scribing member may be manually rotated.

A small block 13 is formed on or secured to the lower end of spring arm 5, and the pencil attachment 6 may have a shank portion engaging in a recess 15 in block 13 and secured therein by means of screw 16 and nut 17.

The pencil attachment 6 is provided in the usual manner with a removable lead or pencil point 18. The instrument further comprises an adjusting screw 19 threaded in the block 13 and engaging or bearing against sleeve 8 at its inner end so that by screwing said adjusting screw in or out the distance between the scribing means and the central member may be varied so as to permit different sized figures to be drawn. All of the parts above described are found in the ordinary type of "pile driver" or self-adjusting spring bow compass.

According to my invention, the instrument is further provided with a template member 22, which is shaped exteriorly to correspond to the figures to be drawn and which is adapted to grip the tapering portion 23 at the lower end of the central member 1 as indicated at 23', upon being forcibly pushed on to said member, and to extend upwardly around the lower portion of sleeve 8, fitting loosely around said sleeve so as to permit the sleeve to turn without turning the template member. If desired, the template member may be permanently secured to the central member, as by welding or otherwise, but in general I prefer to make the same detachable therefrom in order to permit the use of templates of different sizes or shapes with the same instrument. Suitable guide means are provided on the scribing member for engaging the surface of the template member. Such guide means are preferably adjustable so as to provide for varying the size of the figure to be drawn, and may advantageously comprise an adjusting screw 24 threaded in the upper portion of the scribing means 6 as shown. A knurled lock nut 25 is also preferably provided for holding the adjusting screw in the position to which it is set.

In the operation of the above described device for the purpose of drawing or inscribing hexagons, the adjusting screw 19 is adjusted so as to hold the scribing member at the desired distance from the central rod. Adjusting screw 24 is then adjusted so as to just touch or press very lightly against one of the flat surfaces of template member 22, as indicated in Fig. 4, and lock nut 25 is tightened so as to hold the adjusting screw in this position. If the central member 1 is held in fixed position by means of handle 3, and the scribing member is revolved by means of the knurled head 25, the inner end of screw 24 will follow the shape of template member 22, and the scribing means such as pencil point 18 will inscribe upon the paper or other material 26 a hexagon, as indicated at 27.

It will be evident that the instrument may also be used in the ordinary manner of a spring bow compass, for drawing circles, by simply screwing the adjusting screw 24 outwardly so that it does not engage the template member 22.

In Fig. 6 I have shown a square template member 22' which is adapted for the drawing or inscribing of squares as indicated at 29.

A pen attachment 30 is indicated in Fig. 7, which is also provided with a shank portion 14' for mounting on block 13 and is provided with a threaded opening 31 for receiving the adjusting screw 24 or a similar adjusting screw. Such pen attachment may therefore be substituted for the pencil attachment shown in Fig. 1, and the term scribing means as used herein should therefore be understood to include either pen or pencil means or any other means for marking or inscribing the desired figure.

In Fig. 8 I have illustrated a modified form of the invention in which the tubular sleeve 8'' extends only to a position somewhat below the adjusting screw 19, and in which the template member 22'' fits fairly snugly around the central rod 1 below the lower end of said sleeve. A set screw 33 may advantageously be provided for rigidly securing the template member 22'' to the central member 1. In this form of the invention the adjusting screw 24 is shown as threaded in block 13 instead of in the upper portion of the pencil or pen scribing attachment. One advantage of this modification is that the separate pen and pencil attachments do not need to be threaded and provided with separate adjusting screws.

I have also shown, as in Fig. 9, that the template member may be made elliptical in shape so as to provide for the drawing and inscribing of ellipses and it will be apparent that any suitable shape of template member may be employed in connection with either the form of the invention shown in Fig. 1 or that shown in Fig. 8.

I claim:

1. A drafting instrument comprising a central member, a template member secured thereto, a scribing member, means secured to said scribing member and mounted for rotation about said central member, said scribing member having scribing means thereon and also having means tending to hold said scribing means inwardly toward said central member, and an adjusting screw mounted on said scribing member for movement toward or away from said template member and having its inner end adapted to slidably engage the outer face of said template member so as to limit inward movement of the scribing means.

2. An attachment for a self-adjusting spring bow compass having a central member and a sleeve rotatably mounted thereon, said central member projecting somewhat below the lower end of said sleeve, said attachment comprising a template member formed to fit loosely over the lower portion of said sleeve and to engage tightly with the projecting portion of said central member.

3. A drafting instrument comprising an

elongated central member, a sleeve rotatably mounted on said central member and extending throughout the major portion of the height thereof, a template member secured to the lower portion of said central member and extending upwardly around the lower portion of said sleeve and having its outer face formed as a template, a scribing member secured to said sleeve and having scribing means at its lower end, means tending to hold said scribing member inwardly toward template member, and a guide member mounted on said scribing member and extending inwardly therefrom to engage said outer surface of the template member.

15 4. A drafting instrument as set forth in claim 3, said guide member comprising a screw threaded in said scribing member for inward and outward adjustment thereof.

20 5. A drafting instrument comprising a central member, a template member secured thereto, a scribing member, bearing means secured to said scribing member and mounted for rotation on and about said central member, scribing means on said scribing member, means tending to hold said scribing means inwardly toward said central member, an adjusting screw mounted on said scribing member and adapted to engage said template member so as to limit inward movement of the scribing means, and another adjusting screw mounted on said scribing member and adapted to engage said bearing means, whereby said scribing member may be guided, upon rotation thereof, by engagement of one or the other of said adjusting screws with said template member or said said bearing means.

25 6. A drafting instrument comprising a vertical rod pointed at its lower end, a template member secured to said rod, a sleeve rotatably mounted on said rod, scribing means, means connecting said scribing means to said sleeve and tending to resiliently hold said scribing means inwardly toward said rod, and an adjusting screw threaded in said scribing means for movement toward or away from said template member and having its inner end adapted to slidingly engage the outer face of said template member so as to limit the inward movement of the scribing means and cause said scribing means, upon rotation, to follow the shape of said template member.

30 7. A drafting instrument as set forth in claim 6, and comprising in addition another adjusting screw on the scribing means having its inner end adapted to engage said sleeve to cause said scribing means, upon rotation, to follow a circular path.

35 In testimony whereof I have hereunto subscribed my name this 19th day of February, 1927.

HARRY LEE CORWIN.
